US00D796244S

(12) **United States Design Patent** (10) **Patent No.:** **US D796,244 S**
McLean et al. (45) **Date of Patent:** **** Sep. 5, 2017**

(54) **BEVERAGE PRESS**

(71) Applicant: **ESPRO, INC.**, Vancouver (CA)

(72) Inventors: **Christopher R. McLean**, Vancouver (CA); **Bruce A. Constantine**, North Attleboro, MA (US)

(73) Assignee: **ESPRO, Inc.**, Vancouver (CA)

(**) Term: **15 Years**

(21) Appl. No.: **29/554,410**

(22) Filed: **Feb. 11, 2016**

(51) LOC (10) Cl. **07-01**

(52) U.S. Cl.

USPC **D7/317; D7/319**

(58) **Field of Classification Search**

USPC ..... D7/316-322, 598, 600, 536, 507; 222/188, 465.1, 713; D23/209 CPC A47J 41/0027; A47J 31/50; A47J 45/0077; A47J 31/053; A47J 31/20; A47J 31/02; A47J 45/10; A47J 31/14; A47J 411/02; A47J 31/38; A47G 19/22; A47G 19/12

(57) **CLAIM**

The ornamental design for beverage press, as shown and described.

DESCRIPTION

FIG. 1 is a front view of the ornamental design for a beverage press;

FIG. 2 is a left side view thereof;

FIG. 3 is a rear view thereof;

FIG. 4 is a right side view thereof;

FIG. 5 is a top view thereof;

FIG. 6 is top, left-side perspective view thereof;

FIG. 7 is a right-side perspective view thereof; and,

FIG. 8 is a bottom view thereof.

The broken lines in each of the figures are for environmental purposes only and form no part of the claimed design.

1 Claim, 8 Drawing Sheets
